CLARENCE P. COWAN, OF MONTREAL, QUEBEC, CANADA, ASSIGNOR, BY MESNE ASSIGNMENTS, TO THE PATENT AND LICENSING CORPORATION, OF BOSTON, MASSACHUSETTS, A CORPORATION OF MASSACHUSETTS

SIDING SHINGLES

Application filed April 22, 1929, Serial No. 357,246. Renewed November 22, 1932.

This invention relates to new and useful improvements in shingles and particularly to shingles used for covering walls or sidings and the object of the invention is to provide shingles which will simulate brick when laid on a wall.

According to my invention, I provide a shingle of the usual shape with slots extending inwardly from one edge. The shingles are each made in two colours one colour being the same as brick, while the other may be left black or the colour of mortar. The shingles when laid on a wall, show a plurality of rectangles substantially the same size as the side of a brick, each surrounded by a border approximately the same thickness as the thickness of mortar usual in a brick wall.

In the drawing which illustrates my invention,

Figure 1 is a side elevation of a wall covered with my improved type of shingle.

Figure 2 is a perspective view of one of my improved shingles.

Referring more particularly to the drawing, I have shown the shingle with different shades of stippling, as this will facilitate the reading of the drawing and also bring out very clearly where the improvement lies. The shingle designated 11 is of substantially rectangular form with slots 12 cut therein at spaced intervals and from the edge 13. The main body of the shingle is of the usual construction, that is a felt base covered or saturated with a waterproofing compound such as asphalt. The slots 12 are preferably but not necessarily made deeper than the depth of the ordinary standard brick. The surface which is exposed to the weather is covered with a wear resisting material of granular

form. The granular material used is of two different colours, one the same colour as the brick it is desired to simulate, while the other colour is made the same as mortar, or black, the colour of the asphalt. The slots as will be seen divide one side of the shingle into tabs and the brick colouring thereon preferably does not extend the full depth of the slots so that when laid on a wall, rectangular brick coloured surfaces are exposed. In the shingle detailed in Figure 2, two tabs are shown, but

this number may be increased if so desired by lengthening the shingle strip and increasing the number of slots. When laying the shingles on a wall, plain black or mortar coloured shingles 14 are first laid along the lower edge of the wall. The two coloured shingles are then used and laid in the usual manner, with the lower edges of the lowermost course spaced above the bottom edge of the shingles 14, about three eighths of an inch or the usual thickness of mortar. In laying all the other courses of the two coloured shingles, the lowermost edges of the shingles of each course are spaced above the line 15 of the shingles of the adjacent overlapped course. The line 15 is provided by the different colouring of each shingle. The space is equal to the usual thickness of mortar used in brick walls. It will also be seen from Figure 1 that the slots are arranged in staggered form throughout the wall so that the wall 16 when covered with the shingles will have the appearance of a brick wall.

A wall covered with my improved shingle laid in the manner shown in Figure 1 will greatly enhance the appearance of a wall and a house with the walls covered in such a manner will have the general appearance of a brick or brick encased house.

The colours used in the manufacture of the shingle may be red and black, or any desired combination which will simulate the combination of a brick colour and a mortar colour.

Having thus described my invention, what I claim is:

1. A wall comprising horizontal courses of shingle strips, each strip having a plurality of tabs formed along the lower edge, the tabs being divided by slots, said tabs being brick coloured to a depth slightly less than the depth of the slots, the remaining part of the shingle being of a mortar colour, the courses being laid with the slots of each course staggered with the slots of the adjacent courses, and with the tabs of each course overlapping the mortar coloured body portions of a subjacent course to expose vertical strips of mortar colour through the slots, and also being

laid with the lower edge of each course spaced from the upper margin of the brick coloured tabs of a subjacent course to expose horizontal strips of mortar colour thereby simulating the vertical and horizontal mortar joints of a brick wall.

2. A wall comprising horizontal courses of shingle strips, each strip being made of fibrous material covered with a waterproofing compound and one surface covered with a granular wear resisting material, said shingle having slots along one edge dividing it into a series of tabs each substantially the length of a brick, said tabs being coloured to simulate brick, the depth of the colouring from the slotted edge being less than the depth of the slot, the remaining part of the shingle being of a colour to simulate mortar when laid in a wall, the courses being laid with the slots of each course staggered with the slots of the adjacent courses, and with the tabs of each course overlapping the mortar coloured body portions of a subjacent course to expose vertical strips of mortar colour through the slots, and also being laid with the lower edge of each course spaced from the upper margin of the brick coloured tabs of a subjacent course to expose horizontal strips of mortar colour thereby simulating the vertical and horizontal mortar joints of a brick wall.

3. A wall comprising overlapping horizontal courses of shingle strips, each strip being made of fibrous material covered with a waterproofing compound and one surface covered with granular wear-resisting material, said shingle having slots along one edge dividing it into a series of tabs each substantially the length of a brick, said tabs being colored to simulate brick, the remaining portions of the strip carrying a band of a color to simulate mortar when laid in a wall, the courses being laid with the slots of each course staggered with the slots of adjacent courses, and with the tabs of each course overlapping the mortar colored body portion of a subjacent course to expose vertical strips of mortar color through the slots, and also being laid with the lower edge of the brick colored areas of each course spaced from the upper margin of the brick colored tabs of a subjacent course by horizontal strips of mortar color, thereby simulating a brick wall with vertical and horizontal mortar joints.

55 In witness whereof, I have hereunto set my hand.

CLARENCE P. COWAN.
